UNITED STATES PATENT OFFICE.

PHILIP KRASNO, OF MILWAUKEE, WISCONSIN.

INTERNAL-COMBUSTION-ENGINE VALVE.

Application filed June 15, 1925. Serial No. 37,229.

This invention relates to internal combustion engine valve construction.

In internal combustion engine operation it is frequently the case that on the beveled seats of the valves carbon collects and interferes with the seating of the valve either temporarily or permanently, thus lowering the compression and also the effective pressure of the explosion.

10 This invention is designed to overcome the above noted defects and objects of such invention are to provide a novel form of internal combustion engine valve construction which will eliminate the difficulties due to 15 carbon and other deposits, which will accurately seat at all times and under all conditions, which will cut away any carbon that may accumulate and will find a secure seat for itself, and which will thus increase the 20 efficiency of the engine in a marked degree.

An embodiment of the invention is shown in the accompanying drawings, in which:—

Figure 1 is a sectional view through a portion of an internal combustion engine 25 showing one form of valve.

Figure 2 is a view from the under side of such valve showing the valve detached from the valve seats and associated parts.

Figure 3 is a view of a modified form.

30 Figure 4 is a view of a further modified form showing the application of the valve to old styles of engines.

Figure 5 is an enlarged sectional view through an edge of the valve.

35 Referring to the drawings, it will be seen that 1 indicates a portion of an engine block having a port 2 therethrough. Preferably, a hardened liner or valve seat 3 is screwed into the upper end of the port 2 and is provided with an upper flat face and with a threaded downwardly extending sleeve 4 cooperating with a correspondingly threaded portion of the engine block. The valve comprises an upper disk 5 preferably integral with the valve stem 6. This disk is provided with a downwardly turned flange 7 whose lower edge is formed like a dull chisel. It has converging sides, as shown in the drawings and a slightly rounded bottom of small area contacting with the valve seat 3.

In operation, this valve will cut through any carbon that may collect on the valve seat and due to the narrow contacting area, will exert a sufficiently high pressure per unit area to effect complete and adequate

sealing. It may not be found desirable to go to the expense of a separate hardened valve seat 3 for the valve. In this case the valve cooperates directly with the casting 60 1' to close the port 2, as shown in Figure 3, and although this construction is necessarily not as long lived as that shown in Figure 1, it has been found to give excellent results even for an extended period greatly exceeding the usual period of wear of the ordinary types of valves.

In the form shown in Figure 4, a portion of a conventional type of cylinder block is illustrated and indicated by the reference 70 character 1''. It is provided with a beveled seat 8 which received the old style of beveled valve. However, the valve 5 is made of sufficient size to reach beyond the beveled surface 8 and to contact directly with the 75 casting.

It has been found from actual extended tests conducted with this type of valve that the efficiency of a conventionally made motor was increased in a marked degree by 80 the insertion of the type of valve disclosed. The compression was found to be very much improved as well as the effective pressure obtained on explosion. The results were particularly noticeable even in extremely 85 cold weather and it was found that due to the improved seating of the valves that the motor would start very much more readily even in below-zero weather, whereas the old style of motor was found extremely difficult, frequently impossible, to start.

These valves have been in successful and continuous operation for a great length of time, in daily use, and have proven very efficient in actual use. In addition to this 95 they have been found to outwear the ordinary type of valve many times between grinding periods.

It has been found that valves for internal combustion engines seat with greater certainty as the area of the seat is reduced. If the valve is beveled as to wedge in a beveled seat as in the usual construction, any carbon or foreign matter will hold the valve open and will be effective in preventing 100 an adequate compression for the engine contrary to the usual opinion in these matters. I have found through actual experiments conducted with valves of internal combustion engines that the smaller the seat surface, the more complete sealing results. It 110 is, therefore, clear that the valve forming

the subject matter of this invention conforms to the theory and the actual results obtained by my experiments and operates in a manner to secure perfect sealing under all 5 conditions.

These facts are conclusively borne out by the result of extended operation tests conducted with a motor on which these valves were applied, as described above.

10 It will be seen, therefore, that a novel form of internal combustion engine valve has been provided which is not unseated by particles of carbon, but which will cut its way through the carbon and secure a very 15 firm and adequate seat, thus markedly increasing the efficiency of the motor.

Although the invention has been described in considerable detail, it is to be understood that the invention may be variously embodied and is, therefore, to be limited only 20 as claimed.

I claim:

1. A valve for an internal combustion engine, said valve comprising a stem, a disk

formed integrally with said stem and having an inwardly directed peripheral flange, said flange having converging inner and outer walls and terminating in a relatively restricted surface, said restricted surface being rounded, whereby it may seat 25 upon a flat surface without cutting.

2. In an internal combustion engine the combination of a cylinder block having a port therein, a separate and distinct valve seat secured within said cylinder block at 30 said port and having a flat face, a valve comprising a disk for controlling said port, said disk having an inwardly directed marginal flange having converging side walls, said flange being adapted to contact at its 35 outer edge with the flat face of said valve seat to seal said port.

In testimony that I claim the foregoing I have hereunto set my hand at Milwaukee, in the county of Milwaukee and State of 40 Wisconsin.

PHILIP KRASNO.
